LOCOMOTIVE TENDER

Charles J. Surdykowski, Tuckahoe, N. Y., now by
judicial change of name Charles J. Surdy, as-
signor to Standard Stoker Company, Inc., a cor-
poration of Delaware

Application November 22, 1930, Serial No. 497,345

20 Claims. (Cl. 105—234)

This invention relates to a novel locomotive tender construction peculiarly adapted to receive stoker mechanism.

It is an object of the invention to provide in a locomotive tender a forwardly and upwardly tilted stoker trough formed as an integral unit with the tender frame, and more particularly to have a portion of the trough formed within the frame itself.

10 It is a further object of the invention to provide increased coal space in a stoker equipped locomotive tender by forming a portion of the stoker trough within the frame thereby increasing the depth of the fuel bin.

15 It is a further object of the invention to provide an alcove formed in the tender frame at the rear of the trough to receive drive mechanism whereby the stoker fuel conveying mechanism may be operated directly from its rear-
ward end.

20 To the above and other ends the invention consists in the parts and arrangement of parts and in their relation and association one with the other or in combination as hereinafter described and as illustrated in the accompanying drawings, in which

25 Fig. 1 is a central longitudinal vertical section through a portion of a locomotive tender with a portion of the stoker mechanism and the drive mechanism as applied thereon;

30 Fig. 2 is a sectional view on the line 2—2 of Fig. 1;

Fig. 3 is a sectional view on the line 3—3 of Fig. 1;

35 Fig. 4 is a sectional view on the line 4—4 of Fig. 1; and

Fig. 5 is a sectional view on the line 5—5 of Fig. 1.

30 Referring to the drawings, the locomotive tender is indicated generally by the numeral 10 and is provided with the main underframe structure 11, the deck 12, the fuel bin 13 and the water space 14. The tender main underframe structure 11 comprises the base plate 15, the top plate 16 and connecting ribs 17. The invention is shown and described in its preferred form as applied to a tender having a water bottom frame, it will be obvious, however, that the invention is not so limited and is equally applicable to tenders having other than water bottom frames.

35 The fuel bin and water space are separated from each other by the side slope sheets 18 and 19, the rear slope sheet 20 and the fuel trough 21. The trough 21, which may take any suitable cross sectional form, preferably V-shaped,

comprises the sidewalls 22, 23, provided with the flanges 24, 25 respectively and the rear wall 26 provided with the flange 27. The flanges 24, 25 and 27 are attached to the side slope sheets 18 and 19 and the rear slope sheet 20 respectively by suitable water-tight fastening means.

40 The top of the trough 21 is closed by slide plates 28 which may be moved from covering position as the supply of fuel becomes depleted permitting fuel to drop into the trough by gravity.

45 The trough 21 is formed as an integral unit with the tender underframe structure 11 and inclines upwardly from its rearward to its forward end. At its rearward end, the bottom of the trough merges into the base plate 15 of the frame, and at its forward end the bottom of the trough is slightly above the top plate 16 of the frame. That portion of the trough 21 that extends below the top plate 16 forms virtually a 50 depression therein, the sides of the depressed portion of the plate 16 forming the sidewalls of the trough and the rearward portion of the depression forming the rear wall of the trough. It has been customary to mount the trough above the tender frame and generally in a horizontal plane. The innovation proposed by my invention permits lowering of the trough thereby increasing the depth of the coal bin and its capacity, requiring fewer refueling stops on long runs. The lowering of the trough permits the practice of 55 further economy in the use of a shorter trough and conveyor screw than is possible in prior constructions in fuel bins of the same capacity.

50 A screw conveyor 29 having an extended shaft 29a is mounted in the trough 21, and conveys fuel forwardly against the crusher 30, arched over the forward end of the screw 29, where it is reduced to a suitable size for firing. Suitable conveying mechanism carries the fuel forwardly from 55 the trough to a firebox where it is delivered by suitable and well known means. The extended shaft 29a is mounted in a bearing 31 formed in the rear wall of the trough 21.

55 A water tight compartment or alcove 32 is formed in the tender underframe structure 11 rearward of the trough 21 and comprises an irregular front wall 33, the rear wall 34, sidewalls 35 and 36, and the top wall 37 which is formed by a portion of the tender frame top plate 60 16. The bottom of the alcove 32 is open to permit access to the alcove from beneath the tender. Housed in the alcove 32 is the small high speed engine 38 and stoker drive mechanism. Motion is transmitted to the screw shaft 29a from the 65

drive shaft 39, which in turn is operated through suitable enclosed gearing 40 by the engine 38. The screw shaft 29a and the drive shaft 39 are joined by the coupling member 41. By this construction the stoker conveying mechanism is operated directly from its rearward end, eliminating the use of flexible or universal driving connections between the engine and conveyor and the consequent loss in efficiency. The engine and conveyor drive mechanism are easily and conveniently accessible for purposes of inspection, repair and replacement.

I claim:

1. A locomotive tender frame comprising a horizontal main under-frame plate member, and a rearwardly and downwardly extending depression in said plate member forming a stoker trough.
2. A locomotive tender frame comprising a horizontal plate member, a rearwardly and downwardly extending depression in said plate along the vertical longitudinal center line thereof, the walls of said depression continuing upwardly and forwardly above the surface of said plate to form a stoker trough with said depression.
3. A locomotive tender frame comprising a base plate, a top plate, ribs connecting said base plate and said top plate and a stoker trough formed with said tender frame, a portion only thereof being included between said top plate and said base plate, and ribs connecting said trough and said base plate.
4. A locomotive tender frame comprising a base plate, a top plate, ribs connecting said base plate and said top plate, a rearwardly and downwardly extending depression in said top plate along the vertical longitudinal center line thereof, the walls of said depression continuing upwardly and forwardly above said top plate to form a stoker trough with said depression.
5. In a locomotive tender, a main underframe structure and a downwardly opening alcove formed therewith entirely included within the confines of said main underframe, for receiving stoker drive mechanism.
6. A locomotive tender frame comprising a base plate, a top plate, ribs connecting said base plate and said top plate, and an alcove formed within said frame and entirely included between said base plate and said top plate and opening through said base plate.
7. In a locomotive tender, the combination of a main underframe structure, a stoker trough formed therewith, and an alcove formed within the confines of said main underframe rearwardly of said trough and opening downwardly and exteriorly of the tender.
8. A locomotive tender main under-frame comprising a base plate, a top plate, ribs connecting said base plate and said top plate, a depression in said top plate forming a stoker trough, and an alcove formed in said frame rearward of said trough and entirely included between said top plate and said base plate, said alcove opening downwardly through said base plate.
9. The combination in a locomotive tender, of a main under-frame structure, a depression in said main under-frame structure forming a stoker trough, and a stoker drive mechanism housing rearward of said trough depending and supported from said main under-frame structure.
10. The combination in a locomotive tender, of a main under-frame structure, a downwardly opening alcove formed with said main under-frame structure and a stoker drive mechanism housing depending and supported from said

main under-frame structure and mounted in said alcove.

11. The combination in a locomotive tender, of a main under-frame structure, comprising a base plate, a top plate and ribs connecting said base plate and said top plate, an alcove formed with said frame and entirely included between said base plate and said top plate and opening downwardly through said base plate, and a stoker drive mechanism housing depending from said main under-frame structure and mounted in said alcove.

12. The combination in a locomotive tender, of a main under-frame structure, a stoker trough formed therewith, at least a portion of said trough extending below the top of said main under-frame structure, and a stoker drive mechanism housing rearward of said trough depending and supported from said main under-frame structure.

13. In a locomotive tender the combination of a main under-frame structure including a base plate, a top plate and ribs connecting said base plate and said top plate, a stoker trough formed with said main under-frame, an alcove formed in said main under-frame rearward of said trough, entirely included between said base plate and said top plate and opening through said base plate, and a stoker drive mechanism housing mounted in said alcove.

14. In a locomotive tender the combination of a main under-frame structure including a base plate, a top plate and ribs connecting said base plate and said top plate, a stoker trough formed with said frame, at least a portion of said trough being included between said base plate and said top plate, an alcove formed in said frame rearward of said trough, entirely included between said base plate and said top plate and opening through said base plate, and a stoker drive mechanism housing mounted in said alcove.

15. The combination in a locomotive tender, of a main under-frame structure, a stoker trough formed therewith, a downwardly opening alcove formed with said main under-frame structure rearwardly of said trough and a stoker drive mechanism housing depending and supported from said main under-frame structure and mounted in said alcove.

16. In a locomotive tender, the combination of a fuel bin, an open mouth stoker trough beneath and communicating with said bin, said trough sloping downwardly from front to rear, and a plurality of movable plates forming a floor portion for said bin and a closure for the open mouth of said stoker trough, said plates sloping downwardly from front to rear.

17. In a locomotive tender, the combination of a fuel bin, an open mouth stoker trough beneath and communicating with said bin, said trough being angularly disposed with respect to the horizontal, and a plurality of movable plates forming a floor portion for said bin and a closure for the open mouth of said stoker trough, said plates being disposed at substantially the same inclination as said stoker trough.

18. In a locomotive tender, the combination of a fuel bin, an open mouth stoker trough beneath and communicating with said bin, said trough sloping downwardly from front to rear, and a plurality of slidable plates forming a floor portion for said bin and a closure for the open mouth of said stoker trough, said plates sloping at substantially the same inclination as said stoker trough.

19. In a locomotive tender, the combination of a fuel bin, an open mouth stoker trough beneath

and communicating with said bin, said trough sloping downwardly from front to rear, a substantially horizontal platform at the front of said tender forming a shovelling deck, and a plurality of movable plates forming a floor portion for said bin and a closure for the open mouth of said trough, said plates sloping downwardly and rearwardly from said substantially horizontal platform.

10 20. In a locomotive tender, the combination of a fuel bin, an open mouth trough beneath and

communicating with said bin, said trough sloping downwardly from front to rear, a substantially horizontal platform at the front of said tender forming a shovelling deck, and a plurality of 5 movable plates forming a floor portion for said bin and a closure for the open mouth of said stoker trough, said plates sloping downwardly and rearwardly from said substantially horizontal platform at approximately the same inclination as said stoker trough.

10 CHARLES J. SURDYKOWSKI.
